Patented Dec. 20, 1927.

UNITED STATES PATENT OFFICE.

HENRY JERMAIN CREIGHTON, OF SWARTHMORE, PENNSYLVANIA, ASSIGNOR TO
ATLAS POWDER COMPANY, OF WILMINGTON, DELAWARE. A CORPORATION OF
DELAWARE.

PROCESS FOR THE ECONOMICAL REDUCTION OF COMPOSITE SUGAR-BEARING SOLU-
TIONS.

No Drawing.

Application filed March 26, 1926. Serial No. 97,784.

My co-pending application, Serial No. 97,782, filed March 26th, 1926, which resulted in the grant of Patent 1,612,361 issued December 28, 1926, discloses a process for electrolytically reducing sugars to the corresponding alcohols and, more particularly, the reduction of mannose to mannite. In carrying out said process, an aqueous solution of the sugar to be reduced, and which 10 solution has been rendered conducting by the addition of a suitable sodium or potassium compound, such as the sulphate is placed in the cathodic section of an electrolysis cell, where it constitutes the catholyte. The cathode consists of a body of mercury. During the operation of the cell, the mercury is agitated or stirred, along with the catholyte. The anodic section of the cell is separated from the cathodic section by a porous dia- 15 phragm or cylinder of a nature to prevent the mixing of the catholyte and the anolyte, but of a nature to permit the passage of hydrogen ions from the anodic to the cathodic section, and to permit the passage of hydroxyl 20 ions from the cathodic to the anodic section. An anode, which may advantageously consist of lead or lead that is coated with lead dioxide, is disposed in the anodic section and said section contains an anolyte, such as sodium sulphate for example, in the form of 25 an aqueous solution.

When the electric current is turned on, the sulphate ions are discharged at the lead dioxide anode and these subsequently react 30 with the water, forming oxygen and sulphuric acid in the porous cylinder. In the cathodic section of the cell, sodium ions discharge at the mercury cathode and the resulting sodium or potassium atoms unite 35 with the mercury, forming alkali metal amalgam, which subsequently decomposes the water, forming nascent hydrogen and alkali metal hydroxide. The nascent hydrogen formed in this way reduces the mannose 40 to mannite. Continuous decomposition of this amalgam would tend to increase continuously the alkali content (e. g., sodium hydroxide) of the catholyte. This continuous increase, however, is prevented by the 45 fact that hydrogen ions migrate from the anodic solution into the catholyte and there neutralize the alkali, and hydroxyl ions mi-

grate from the catholyte into the porous cylinder and there neutralize the acid, the result of both neutralizations being the reformation of alkali metal sulphate. In this way a limited amount of alkali metal sulphate is used over and over again. The rates of migration of these ions and other conditions are such that the catholyte remains either alkaline or neutral, and the anolyte remains somewhat acid.

My improved process, as outlined above, is of marked advantage in the economical commercial reduction of composite, sugar bearing solutions. For example, the sugar syrup prepared by standard methods from vegetable ivory, consisting largely of mannose and some glucose and possibly other sugars, may be very readily reduced by the electrolytic method, just described, and the resulting mannite or the mixed alcohols may be separated from the catholyte by proper extraction methods. It has been found to be much cheaper to reduce the syrup of mixed 50 sugars, obtained from vegetable ivory, and then extract the mannite from the product of the reduction process than to separate first the mannose from the mixed sugars and reduce said mannose to mannite. Furthermore, it is not always necessary or desirable to separate the alcohols of the reduction process. While one of the important uses 55 for the mannite that I produce is in the production of nitro-mannite for use in explosives, I find that a highly desirable and very economical explosive of this nature may be produced by first reducing the composite 60 vegetable ivory syrup by the method described, and then nitrating the composite 65 alcoholic product without attempting to separate the mannite from the remainder of the product.

Therefore, by the present application, I 70 desire to claim the above described step of 75 reducing a natural, composite sugar-bearing mixture to the corresponding alcohols and nitrating the composite product. The process of reducing a natural composite sugar-bearing product to the corresponding alcohols, and thereafter separating said alcohols, in contra-distinction to first separating the sugars in the natural product, and then reducing the individual sugars, is being made 80 85 90 95 100

the subject matter of a separate application, Serial No. 221,626, filed on the 23rd day of September, 1927, under Patent Office requirement for division. I also desire to claim the 5 nitration of the product obtained by the reduction of the composite sugar-bearing syrup prepared from natural sources, such as vegetable ivory, dahlia tubers and other natural sources of inulin, corn-cobs and other natural 10 sources of xylose, and the utilization of the nitrated product in the manufacture of explosives, in the way now well known in the art of explosives manufacture.

Having described my invention, what I 15 claim is:

1. The herein described method consisting of reducing a composite sugar-bearing mixture, obtained from natural products, and nitrating the composite alcoholic product.
2. The herein described method consisting of electrolytically reducing a composite sugar-bearing mixture, obtained from natural products, and nitrating the composite alcoholic product.
3. The herein described method which consists of electrolytically reducing the product, which contains a plurality of sugars, obtained from natural sources, to the corresponding alcohols and nitrating the composite alcoholic product.
4. The herein described method which

consists of electrolytically reducing the product, which contains a plurality of sugars, obtained by the hydrolysis of natural substances, to the corresponding alcohols and 35 then nitrating the composite alcoholic product.

5. The herein described method which consists of treating a solution, including a plurality of sugars, together with a sodium or potassium compound, in an electrolysis cell, having a mercury cathode; forming sodium amalgam directly in the cell, which converts the sugars to the corresponding alcohols, and then nitrating the composite al- 45 coholic product.

6. The herein described method which consists of treating a solution, including a plurality of sugars obtained by standard methods from vegetable ivory or other natural sources of mannose, together with a sodium or a potassium compound or mixture of these compounds, in an electrolysis cell, having a mercury cathode; forming alkali metal amalgam directly in the cell, which 50 converts the sugars to the corresponding alcohols, then separating the individual alcohols and then nitrating the composite alcohols. 55

In testimony whereof he affixes his signature.

HENRY JERMAIN CREIGHTON.
